By *J. G. Chauvin & Son, Jr.* Attorney

UNITED STATES PATENT OFFICE.

JOHN H. KILLINGER, OF STEELTON, PENNSYLVANIA.

METALLIC RAILWAY-TIE AND RAIL-FASTENING DEVICE.

SPECIFICATION forming part of Letters Patent No. 784,793, dated March 14, 1905.

Application filed January 9, 1905. Serial No. 240,211.

To all whom it may concern:

Be it known that I, JOHN H. KILLINGER, a citizen of the United States, residing at Steelton, in the county of Dauphin and State of Pennsylvania, have invented new and useful Improvements in Metallic Railway-Ties and Rail-Fastening Devices, of which the following is a specification.

My present invention relates to certain new and useful improvements in metallic railroad-ties and in improved means for fastening the rails thereto.

The objects of the invention are, first, to provide metallic ties of sufficiently strong and durable construction to effectually withstand the heavy strains and loads to which they are constantly subjected in use; second, to provide a tie that can be economically rolled from a metal billet or bar; third, to provide novel means for bracing and strengthening those parts of the tie that are subjected to the heaviest loads and strains, and, fourth, to provide a novel and simple construction of rail-fastening device associated with the ties and adapted to secure firmly the rails in position without the use of spikes.

The invention has in view other more or less important objects, all of which will be made to appear in the following detailed description.

In order to enable those skilled in the art to make and use the invention, I will now proceed to describe the same in detail, reference being made for this purpose to the accompanying drawings, in which—

Figure 1 is a perspective view of a railroad-tie constructed according to my present invention. Fig. 2 is a longitudinal sectional view of the same. Fig. 3 is a transverse section taken on the line 3 3 of Fig. 2. Fig. 4 is a bottom plan view of the tie. Fig. 5 is a perspective view of one of the base-plates, shown detached from the tie. Fig. 6 is a detail perspective of a part of the rail-fastening device.

Referring to the drawings, the reference-letter A designates the main body portion of the tie, which, as will be seen, consists of a channel-iron having a top 1, outwardly and downwardly extending inclined walls 2, and

outwardly-extending longitudinal flanges 3. This channel-iron may be conveniently and economically rolled from a bar or billet by suitable machinery provided for the purpose and can then be cut into the desired lengths. 55

In order to firmly brace the channel-iron thus formed and prevent the sides from spreading, I provide at each end thereof a suitable base-plate, one of which is shown in detail perspective in Fig. 5 of the drawings, each 60 base-plate consisting of a body portion 4, having side flanges 5 and upwardly turned or bent end wings 6, the said end wings corresponding in shape and size to the internal diameter and form of the channel-iron or tie. 65 One of these base-plates extends across the open bottom of the channel-iron at each end thereof and is secured in position by bolts or rivets 7, extending through the flanges 3 and 5 of the channel-iron and base-plate, respectively, and the end wings project up into the channel-iron, and thus serve to support the same from within. As will be seen by referring to Fig. 2 of the drawings, the base-plates are separated from each other, so as to provide an open space about midway of the tie or channel-iron, and when the latter is placed in position for use this space will be filled with earth, stone, and the like to prevent the tie from riding or shifting. 75

The tie constructed as above described will be firm and rigid and sufficiently strong to withstand the strains and loads to which it is subjected during use.

Secured to the top 1 of the tie, at each end thereof, is a pair of blocks or plates 8, each having its upper face gradually tapering away from one end toward the sides and toward the opposite end, as shown, and each provided with a longitudinal slot or recess 9, extending through the same and in register with a corresponding slot 10 in the top of the channel-iron. As shown in the drawings, there are two of these blocks or plates 8 at each end of the tie, and they are spaced apart or separated sufficiently to receive between them the base or flange of the rail 12. 95

I will now proceed to describe my improved rail-fastening means employed in connection with the tie above described, and as the parts 100

employed are duplicates of each other it will suffice to describe but one set of these devices, it being understood, of course, that two sets are employed at each end of the tie, the arrangement being such that the rail will be embraced upon opposite sides.

The reference-numeral 13 designates a rail-fastening element, consisting of a head having outwardly-extending ends 14 and 15, respectively, and a transverse slot 16. As more clearly shown in Fig. 2 of the drawings, it will be seen that two of these elements are employed at each end of the tie, and they are arranged to embrace opposite sides of the rail 12. These fastening elements are each let down into the slots or recesses 9 and 10 in one of the blocks 8 and channel-iron 1, and when in position the outwardly-extending end 14 of each element overhangs a part of the base-flange of the rail 12, while the other end, 15, thereof rests upon and is supported by a shoulder 17, formed by cutting the slot 9 in the block 8 longer than the slot 10 in the top of the channel-iron. The heads of the rail-locking elements 13 are seated entirely within the slots 9 in the blocks 8 and are thus protected from accidental derangement or breakage, which is considered an important feature of the invention.

Extending transversely through openings 18 in the inclined side walls 2 of the channel-iron and through the slot 16 in each rail-fastening element is a wedge-key 19, having at one end a threaded stem 20 and nut 21. In order to provide a flat bearing-face for the nut 21, I employ a wedge-block 22, having an opening 23 for the stem 20 and an inclined wall 24, corresponding to the inclined side wall 2 of the channel-iron, said wedge-block also having a recess 25 to receive the end of the wedge-key 19 should the latter in the tightening operation protrude through the opening 18 in the inclined side wall of the channel-iron.

In laying a track with my improved tie and rail-fastening device the ties are first set in the usual manner and the rails 12 laid thereon between the plates or blocks 8. The rail-fastening elements 13 are then dropped into the slots provided for the purpose, the wedge-keys 19 inserted as described, and the nuts 21 then applied. It will be apparent that by tightening up the nuts the wedge-keys will be drawn in and the fastening elements drawn down, so that the heads 14 will tightly embrace the base-flange of the rails 12. It will be apparent from the foregoing that a track can be quickly laid and repairs rendered easy, owing to the fact that no spikes or like fastening device for the rails are employed.

I do not wish to be understood as limiting myself to the precise construction and arrangement of parts as herein shown and described, except as I may be limited by the following claims, as I am aware that minor

changes may be made without departing from the spirit of the invention.

What I claim, and desire to secure by Letters Patent, is—

1. A metallic railway-tie, comprising a channel-iron and base-plates secured to the base thereof at opposite ends of the tie, each base-plate having integral tongue-pieces bent upward and disposed within the channel-iron and serving to brace the tie internally. 75

2. A metallic railway-tie, comprising a channel-iron having base-flanges, and plates secured to said flanges at opposite ends of the tie, each plate having integral tongue-pieces bent upward and disposed within the channel-iron and serving to brace the tie internally. 80

3. A metallic railway-tie, comprising a channel-iron having inclined side walls and base-flanges, and strengthening base-plates extending across the open bottom of the channel-iron at opposite ends thereof, each base-plate having side flanges secured to the base-flanges of the channel-iron and provided with upturned end wings, said wings corresponding in shape and size to the interior of the channel-iron and bearing against the inner walls thereof so as to brace the same from within. 85

4. A railway-tie, comprising a channel-iron having a pair of separated slotted blocks at each end thereof, rail-fastening elements seated wholly within the slots in the blocks and having portions adapted to overhang the flange of the rail located between the blocks, and means passing through the channel-iron and engaging said fastening elements for drawing them into clamping engagement with the rail. 95

5. A railway-tie, comprising a channel-iron having a pair of separated and longitudinally-slotted blocks secured to the top thereof at each end, the side walls of said channel-iron being provided with coincident openings, rail-fastening elements seated wholly within the slots in the blocks and each element having a depending slotted portion and a portion adapted to embrace the flange of a rail, a wedge-key extending transversely through the coincident openings in the channel-iron and through the depending slotted portion of each fastening element, said wedge-keys each having a threaded stem at one end, and a nut engaging each stem for the purpose specified. 105

6. A railway-tie, comprising a channel-iron having a pair of separated and longitudinally-slotted blocks secured to the top thereof at each end, the side walls of said channel-iron being inclined and provided with coincident openings, rail-fastening elements seated wholly within the slots in the blocks and each element having a depending slotted portion and a portion adapted to embrace the flange of a rail, a wedge-key extending transversely through the coincident openings in the channel-iron and through the depending slotted portion of each fastening element, said keys 110

each having a threaded stem at one end, a nut engaging each stem, and a wedge-block interposed between each nut and a side of the channel-iron.

5 7. A railway-tie, comprising a channel-iron having slots in the top thereof and inclined side walls provided with coincident openings, rail-fastening elements each having a depending slotted portion extending through one of said slots and a portion adapted to embrace the flange of a rail, a wedge-key extending transversely through the coincident openings in the channel-iron and through the depending slotted portion of each fastening element,

15 said keys each having a threaded stem at one end, a nut engaging each stem, and a wedge-block interposed between each nut and a side of the channel-iron, said wedge-block being provided with an opening for the stem and a longitudinal recess to receive a part of the 20 wedge-key.

In testimony whereof I have hereunto set my hand in presence of two subscribing witnesses.

JOHN H. KILLINGER.
